UNITED STATES PATENT OFFICE.

IRA F. PECK, OF PROVIDENCE, RHODE ISLAND.

SPINDLE-HOLDER FOR DYEING YARN IN COPS.

SPECIFICATION forming part of Letters Patent No. 434,136, dated August 12, 1890.

Application filed May 21, 1890. Serial No. 352,647. (No model.)

To all whom it may concern:

Be it known that I, IRA F. PECK, a citizen of the United States, residing at Providence, in the State of Rhode Island, have invented 5 a new and useful Improvement in Spindle-Holders for Dyeing Yarn in Cops, of which the following is a specification.

In dyeing yarn in cops which are immersed in the dyeing-liquor upon hollow spindles, 10 through which the dyeing-liquor is made to pass by means of a pump, it is very desirable to be able to operate upon a few spindles at a time, while a comparatively large number of spindles are held in the vat of dyeing- 15 liquor ready to be acted upon alternately with the others, and by this means a uniform color will be produced in all of the cops in the vat and the time will be greatly economized; and my invention consists in the em- 20 ployment of a spindle-holder provided in- 25 teriorly with a valve, which is adapted to alternately allow and prevent the passage of the dyeing-liquor through the several cops, so that while a comparatively great number of cops are in the dyeing-liquor only a por- 30 tion of the same will be acted upon by the pump at any one time.

Figure 1 represents an elevation of a spindle-holder provided with my improvement. 35 Fig. 2 is a longitudinal section of the same. Fig. 3 represents a transverse section taken in the line $x x$ of Fig. 1. Fig. 4 is a top view of the clamp for connecting the hose to the spindle-holder. Fig. 5 is a transverse sec- 40 tion of the spindle-holder, showing a modifi- 45 cation. Fig. 6 is a longitudinal section of the same.

In the accompanying drawings, A is a per- 40 forated cylindrical shell, into the perforations 45 a a of which are inserted the short tubes b b, which are adapted to receive the inserting- shank c of the hollow spindle d, upon which the cop is to be placed. The shell A is pro- 50 vided at one end with the hollow head B, 55 which may be screwed upon the end of the tube, and which is provided with a passage e, extending to an opening f at the coupling- joint g. The hose or pipe D is provided with 60 a hollow joint-piece C, which is held against

the head B at the opening f to form a tight 50 coupling-joint at g by means of the hand- clamp E, which is shown separate in Fig. 4. At the opposite end of the shell A is secured 55 the head B', provided with the hollow hub h, and within the bore of the cylindrical shell A and closely fitting the same is placed the valve F, which extends from end to end of the shell A, the said valve being provided at 60 its opposite sides with the openings i i, so that the opposite longitudinal series of spin- 65 dles d d will be acted upon by the vacuum in the chamber G, while the remaining spin- dles around the shell A will be unacted upon. The valve-stem j passes through the hollow hub h, which is provided with a stuffing-box 70 k, and upon the projecting end of the stem j may be placed a gear m, by means of which the valve F may be rotated within the shell A to successively cover and uncover the open- 75 ings to the spindles d d, the shell A being at 80 the same time held stationary by any suit- able means—as, for example, by means of the flattened shank j'—and as the valve F is turned within the shell A the several lon- 85 gitudinal series of spindles which project 75 from the periphery of the shell will be suc- cessively brought under the action of the 80 vacuum employed for causing the dyeing-liquor to flow through the cops placed upon the 85 spindles.

A modification of my invention is shown in 90 Figs. 5 and 6, in which the valve F is adapted 95 for a sliding instead of a rotary movement within the shell A, and in this case the holes i i are arranged to open and close the pas- 90 sage to the several sets of spindles project- 95 ing from the periphery of the shell, and in 95 operating the valve F the shell A is to be held 100 stationary, as before, and the valve moved 100 back and forth, as required, by means of the 105 projecting stem j. When the spindle-holder, 110 with its attached spindles and cops, is placed 115 in a vat of dyeing-liquor, the liquor is to be 120 drawn through the cops upon the spindles d 125 by means of a suction-pump at the end of 130 the hose or pipe D, thus creating a vacuum 135 in the chamber G, which tends to draw the 140 liquor inwardly through the cop.

I claim as my invention—
The combination, with the perforated shell
provided with the hollow spindles, of a valve
located within the hollow shell and adapted
5 to open and close the passages to the hollow
spindles successively, so that the dyeing-liquor
will pass through a portion only of the
spindles at any given time, substantially as
described.

IRA F. PECK.
